ELECTRONIC DOOR OPENING DEVICE
George A. Weible, Detroit, Mich., assignor to Industrial
Electronics Inc., Detroit, Mich., a corporation of
Michigan
Filed Mar. 15, 1961, Ser. No. 95,972
7 Claims. (Cl. 318—478)

The present invention relates to an electronic door opening device, and more particularly to an electronic door opening device in which the use of relays is minimized. Devices for automatically opening doors upon the approach of a person have come into widespread use in recent years as a convenience to customers in railway and air terminals, supermarkets and the like. Conventional devices have comprised a plurality of interlocking relays which operate to control a motor to open and close the door at the desired time. While such conventional devices have in general operated satisfactorily, the use of a plurality of relays has made the devices relatively expensive and the service life has been relatively short because of rapid deterioration of the relays.

The present invention offers a solution to this problem by the use of electronic components instead of relays to thereby lower the cost of the unit and to provide a unit having considerably longer life.

It is, therefore, an object of the invention to provide an automatic door opening device incorporating low cost and durable electronic components.

Another object of the invention is to provide a door opening device having only one relay, thus permitting the use of a high quality relay having a longer life while still staying within the cost structure of such devices.

A further object of the invention is to provide a door opening device having switches operated by persons approaching the doorway, the switches being low-current devices to insure the safety of the users.

Another object of the invention is to provide a door opening device with an extended service life.

Other objects of this invention will appear in the following description and appended claims, reference being had to the accompanying drawings forming a part of this specification wherein like reference characters designate corresponding parts in the several views.

In the drawings:

FIGURE 1 is a view in perspective of a door construction operated by the door opening device of the present invention;

FIGURE 2 is a schematic view of one embodiment of the electrical circuitry of the present invention; and

FIGURE 3 is a schematic view of the circuit controlled by the FIGURE 2 device.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

FIGURE 1 illustrates a typical door structure 10 which is operated to open and close by means of the present invention. The door structure comprises an "in" door 12 and an "out" door 14. The doors 12, 14 are hingedly mounted to swing in and out as is conventional. The "in" door will always swing inwardly and the "out" door will always swing outwardly. Each door is provided with an approach mat 16 and a safety mat 18. Each mat has depressible panels 20, 21 which operate, when stepped on, to close a switch positioned thereunder.

In operation, a person approaching the "in" door from

2

the outside will step on the panel 20, operating the aforementioned switch to trigger the door opening device to cause the door to swing inwardly. As will be appreciated, if a person is already standing on the safety mat 18, it is undesirable to have the "in" door swing inwardly. Consequently, the switch operated by depressing the safety panel 21 is made operative to prevent inward swinging of door 12 until the person moves off the safety mat. Additionally, it is undesirable to have the door swing back to its initial position until the person entering has passed completely over the safety mat. Therefore, the safety switch operated by panel 21 is also adapted to hold the door open until the person has stepped off the safety mat.

The electronic circuit for accomplishing these ends is illustrated in FIGURE 2. Normally open switch 22 is operated by the approach panel 20 and normally open switch 24 is operated by the safety panel 21. The circuit will first be traced assuming the condition where a person steps on the approach mat to close approach switch 22 and where there is no one standing on safety mat 18 with the result that safety switch 24 remains open.

Power is supplied from a suitable source 26 to the primary coil 28 of transformer 30. The transformer 30 is shown as having an iron core 32. A lead 34 extends from one side of the transformer secondary coil 36 and has a branch lead 38 which connects to a resistor 40. The lead 38 then connects to the emitter 42 of a p-n-p power transistor 44. The resistor 40 is for thermal stabilization of the transistor 44. Lead 46 extends from the transistor collector 48 into connection with a capacitor 50 and relay coil 52 which are arranged in parallel. Lead 54 extends from the parallel capacitor and coil to a silicon rectifier 56. Lead 58 extends from the rectifier to lead 60 which connects to the second side of the secondary coil 36. The relay coil 52 operates a first set of contacts 62 which actuate the door opening motor 64 as will be hereinafter explained and a second set of contacts 66 which form part of the present control circuit. The rectifier 56 provides a pulsating D.C. current to operate the coil. The function of the capacitor 50 is to smooth the rectified current to thus increase the reliability of the relay. Current cannot, of course, flow from the emitter 42 to collector 48 unless current is also flowing from the emitter to the transistor base 68. The emitter to base current is controlled by the approach switch 22 and a second control transistor 70.

Lead 72 extends from the base 68 to resistor 74. A second resistor 76 is provided in series with resistor 74 and has lead 78 which extends to the switch 22. Lead 80 extends from the switch 22 to the emitter 82 of the control transistor 70. Lead 84 extends from the collector 86 of the transistor 70 to parallel arranged light 88 and resistor 90. Lead 92 extends from the light 88 and lead 94 extends from the resistor 90 into connection with the lead 60 which connects with the secondary coil 36 of transformer 30.

The above described path provides a complete circuit for emitter to base current of the power transistor 44. This path is closed provided that switch 22 is closed and that control transistor 70 is conducting. Transistor 70 will normally conduct when switch 22 is closed. The emitter to base circuit of this transistor is completed by lead 96 which extends from the base 98 and has a branch 100 with resistor 102 which connects with the lead 60 to return to the secondary coil 36. Consequently, depression of switch 22 will normally cause control transistor 70 to conduct, permitting power transistor 44 to conduct and energize relay coil 52 to open the door.

In the above described circuit, resistor 74 acts to limit the current drawn by transistor 44, resistor 76 is a load resistor for a diode 104, the light 88 and resistor 90 form part of a test circuit, and the resistor 102 is a biasing re-

sistor for the control transistor 70. A biasing resistor 106 is connected by lead 108 from the base 68 of the power transistor 44 to the lead 34 which connects to the secondary transformer coil 36.

When relay coil 52 is energized, it will close its normally open contacts 62 and 66. Referring to FIGURE 3, the contacts 62 comprise a pair of contacts 110, 112 to provide a double break switching action. The double break reduces arcing on opening and results in less contact wear. Closing of the contacts 62 closes a circuit between leads 114, 116. Lead 114 connects to the motor 64. A lead 118 extends from the motor to a source of power 120. The lead 116 is connected to the other side of power 120. It will thus be seen that closing of contacts 62 is effective to energize the motor 64 to open the door. Other control components may be provided in this circuit to control such factors as the rate of door opening and the extent of door movement.

After the door has opened, the person entering will step off the approach mat to pass through the door opening. In so doing, he will release approach switch 22 which will immediately open. Means thus have to be provided to hold the door open for a long enough period to permit the person to walk through and off the safety mat 18. This is accomplished in two steps. First means are provided to hold the door open for a limited time with both switches 22 and 24 open. When switch 24 is closed subsequent to the closing of switch 22, second means are provided to hold the door open for as long as switch 22 is closed.

The means for holding the door open when both switches 22, 24 are open comprise an electrolytic capacitor 122 and the diode 104. Lead 124 extends from the capacitor 122 into connection with the lead 46 which extends from the transistor collector 48. A second lead 126 extends from the other side of the capacitor 122 into connection with lead 72 between the resistors 74, 76. Lead 128 connects the diode 104 between leads 126 and 46. The function of diode 104 is to prevent application of a reverse voltage on the capacitor 122, which would cause excessive wear on the capacitor. In essence, the diode shorts out the capacitor during one half cycle. When switch 22 is opened, capacitor 122 will keep the power transistor 44 in conduction for approximately one and one-half seconds. Continued conduction by transistor 44 will keep the relay coil 52 energized and the door will remain open.

After the elapse of one and one-half seconds, transistor 44 would cease to function. However, by this time it is assumed that the person will have traveled through the door opening and will have depressed safety panel 21 to close switch 24. Closing of switch 24 will close a second path through the circuit to permit emitter to base current flow in the power transistor 44. This path comprises lead 72 from the base 68, resistors 74, 76, lead 78, from which extends lead 132 to switch 24. Lead 132 extends from the other side of the switch 24 to the relay contacts 66. In view of the fact that relay coil 52 is at this time energized, contacts 66 will be closed. Lead 134 extends from the relay contacts to parallel arranged resistor 136 and light 138. The resistor and light form a part of the aforementioned test circuit. Lead 60 extends from the resistor 136 and light 138 to the secondary coil 36 to complete the path for emitter to base current flow of the transistor 44. This path will remain closed as long as the switch 24 is closed. Thus, until the person steps off the safety mat, the door will remain open.

The switch 24 also acts to prevent opening of the door if a person is standing on the safety mat 18 when a second person steps onto the approach mat 16. In this case, switch 24 will be closed before switch 22 is closed. When switch 24 is closed without the previous energization of relay coil 52, a circuit is not completed from the transistor base 68 to power because the contacts 66 of the relay will be in their normally open position. Thus, the door

will not open if switch 24 is closed before closure of switch 22.

If switch 22 is closed subsequent to closure of switch 24, the door will still not open. It will be noted that a resistor 140 is connected by lead 142 between the control transistor base 98 and lead 132. Resistor 140 is selected with a value to bias the transistor 70 to cutoff and prevent operation of this transistor. Thus, both potential paths, through transistor 70 and through relay contacts 66, are open preventing conduction by transistor 44. In view of the fact that transistor 44 must conduct before relay coil 52 will be energized, it will be appreciated that the door will not open under these circumstances.

An alternate method of operating transistor 44 is provided for the case where it is desired to permanently hold the door open. This might be desired, for example, on warm summer days. In this circuit, the base 68 is connected to power via lead 72, resistors 74, 76, lead 144, resistor 146, lead 148, switch 150, and lead 152 which connects to lead 60 and thence to the secondary coil 36. As will be appreciated closure of switch 150 will complete this circuit and excite the transistor 44 to cause opening of the door. The door will remain open until switch 150 is again opened.

25 A test circuit is also provided for trouble shooting the device when it fails to perform. The most frequent problem encountered in service is the shorting out of the switches 22, 24. This may occur because the switches stick in the closed position or foreign material of a conducting nature may cause such shorting. The test circuit comprises normally open test switch 154 having a contact point 156 connected to lead 34. Lead 158 extends from switch 154 into connection with lead 148 which, as previously mentioned, is connected to lead 78. Resistor 146 has a low resistance. The closure of switch 154 places resistor 146 in parallel with resistors 74, 76 and 106. The net resistance of this network is relatively low, permitting the flow of a relatively high current therethrough. This current is high enough to cause lighting of lights 88, 138 if the respective switches 22, 24 are closed. Such closure could, as previously mentioned, be due to a short or sticking of the switch. The resistors 90, 136 are provided in parallel with the lights in order to keep the circuits closed in the event the lights burn out.

45 If light 88 lights, then it may be assumed that switch 22 is shorted. If light 138 lights, then it may be assumed that switch 24 is shorted. If neither light lights, the service man may close switch 22. If the door does not open but light 88 lights, then it can be assumed that the problem is in the transistor 44 circuit. If this is the case, the field can be further narrowed by subsequently closing switch 24. If light 138 then goes on, transistor 44 and the relay are operating properly. The trouble is then in the control circuit operating the motor 64.

The door opening device of the present invention incorporates only two transistors and one relay. It is estimated that this circuit eliminates the necessity for four relays as presently used in conventional devices. The cost of a transistor is approximately one-third that of the relays used. From this, it is evident that there is a considerable cost saving in the present structure. Additionally, there is a considerable reduction in size and it has been found in practice that the present device has a service life of approximately 5 million cycles as compared to 50,000-100,000 in previous devices. Another advantageous feature in the device resides in the use of a low-voltage control transistor which permits the use of low-voltage switches at the mats. Such low-voltage switches eliminate the possibility of a dangerous shock to people walking on the mats.

70 The one relay utilized in the present device is a high quality, relatively expensive relay which will perform in the range of 5 million cycles without failure. The inclusion of such an expensive relay within the price structure of such opening devices is made possible by 75 the cost savings effectuated elsewhere in the system.

Having thus described my invention, I claim:

1. An automatic door-opening transistor circuit comprising first and second transistors each having a base electrode, an emitter electrode, and a collector electrode, the base of the first transistor being connected to the emitter of said second transistor, a normally open switch interposed between said first transistor base and said second transistor emitter, a source of power to excite said first and second transistors to conduct when said switch is closed, a relay coil connected between said first transistor collector and said source of power, said coil being energized when the first transistor conducts, a set of normally open relay contacts operated to close upon energization of said coil, and a circuit including a source of power and a door-opening motor, said relay contacts being interposed in said lastmentioned circuit and being operative upon closure to cause actuation of said motor.
2. An automatic door-opening transistor circuit comprising first and second transistors each having a base electrode, an emitter electrode, and a collector electrode, the base of the first transistor being connected to the emitter of said second transistor, a normally open switch interposed between said first transistor base and said second transistor emitter, a source of power to excite said first and second transistors to conduct when said switch is closed, a capacitor connected between the base and collector of the first transistor, said capacitor being operative to cause conduction of the first transistor for a period of time after opening of said switch, a relay coil connected between said first transistor collector and said source of power, said coil being energized when the first transistor conducts, a set of normally open relay contacts operated to close upon energization of said coil, and a circuit including a source of power and a door-opening motor, said relay contacts being interposed in said lastmentioned circuit and being operative upon closure to cause actuation of said motor.
3. An automatic door-opening transistor circuit comprising first and second transistors each having a base electrode, an emitter electrode, and a collector electrode, the base of the first transistor being connected to the emitter of said second transistor, a first normally open switch interposed between said first transistor base and said second transistor emitter, a source of power to excite said first and second transistors to conduct when said first switch is closed, a relay coil connected between said first transistor collector and said source of power, said coil being energized when the first transistor conducts, first and second sets of normally open relay contacts operated to close upon energization of said coil, the base of the first transistor being connected to said source of power through said second set of relay contacts, a second normally open switch in series with said second set of relay contacts, closure of said second switch subsequent to energization of the relay coil being operative to continue conduction of said first transistor, and a circuit including a source of power and a door-opening motor, said first set of relay contacts being interposed in said lastmentioned circuit and being operative upon closure to cause actuation of said motor.
4. An automatic door-opening transistor circuit comprising first and second transistors each having a base electrode, an emitter electrode, and a collector electrode, the base of the first transistor being connected to the emitter of said second transistor, a first normally open switch interposed between said first transistor base and said second transistor emitter, a source of power to excite said first and second transistors to conduct when said first switch is closed, a second normally open switch and a biasing resistor connected in series from a point be-

tween the base of said first transistor and said first switch to the base of the second transistor, said biasing resistor being operative to prevent conduction by said second transistor when said second switch is closed, a relay coil connected between said first transistor collector and said source of power, said coil being energized when the first transistor conducts, a set of normally open relay contacts operated to close upon energization of said coil, and a circuit including a source of power and a door-opening motor, said relay contacts being interposed in said lastmentioned circuit and being operative upon closure to cause actuation of said motor.

5. An automatic door-opening transistor circuit comprising first and second transistors each having a base electrode, an emitter electrode, and a collector electrode, the base of the first transistor being connected to the emitter of said second transistor, a first normally open switch interposed between said first transistor base and said second transistor emitter, a source of power to excite said first and second transistors to conduct when said switch is closed, a capacitor connected between the base and collector of the first transistor, said capacitor being operative to cause conduction of the first transistor for a period of time after opening of said first switch, a relay coil connected between said first transistor collector and said source of power, said coil being energized when the first transistor conducts, first and second sets of normally open relay contacts operated to close upon energization of said coil, a first lead extending from a point between the base of the first transistor and said first switch to power, said second set of relay contacts being interposed in said lead, a second normally open switch interposed in the first lead between the second set of relay contacts and the base of the first transistor, a second lead extending from the first lead from a point between said second switch and the second set of relay contacts into connection with the base of the second transistor, a biasing resistor interposed in said second lead, closure of said second switch subsequent to energization of the relay coil being operative to continue conduction of said first transistor, closure of said second switch prior to energization of the relay coil being operative, via said biasing resistor, to prevent conduction of said second transistor, whereby said first transistor will not conduct unless said first switch is closed prior to closure of said second switch, and a circuit including a source of power and a door-opening motor, said first set of relay contacts being interposed in said lastmentioned circuit and being operative upon closure to cause actuation of said motor.
6. A device as claimed in claim 5 and further characterized in the provision of a third lead extending directly from the base of the first transistor to the source of transistor power, a third switch interposed in said third lead, closure of said third switch being operative to excite the first transistor to conduct to energize said relay coil.
7. A device as claimed in claim 5 and further characterized in the provision of a test circuit comprising a first electrically-operated signalling device in series with said first normally open switch, a second electrically-operated signalling device in series with said second normally open switch, leads connecting said first and second signalling devices and said first and second switches in parallel to power, and a fourth switch interposed in said test circuit, closure of said fourth switch being operative to complete circuits through said first and second signalling devices when their respective normally open first and second switches are closed.
